UNITED STATES PATENT OFFICE

JOSEF V. PACHER, OF BROOKLYN, NEW YORK, ASSIGNOR TO THE INTERNATIONAL POSTAL SUPPLY COMPANY, OF BROOKLYN, NEW YORK, A CORPORATION OF NEW YORK

INKER

Application filed July 30, 1930. Serial No. 471,788.

The present invention relates to inking rollers, and more particularly to vertical inkers such as are used in mail cancelling machines and similar printing mechanisms. Uniform distribution of the ink as well as automatic delivery in accordance with the speed of the inker in machines of this type is highly desirable. It is an object of the invention to provide for delivery of ink to the ink pad by centrifugal force, the ink being delivered proportionately to the speed of the inker.

It is also an object of the invention to distribute the ink uniformly over the entire surface of the pad, the ink being directed along the inner surface of the pad in such a manner that it reaches all portions thereof.

Other objects will be apparent from the following description taken in connection with the appended drawings in which

Figure 1 is an elevation partly in section of a preferred form of inker embodying the invention, a supply reservoir being shown in connection with the inker;

Fig. 2 is an elevation of the inker and pad, the latter being broken away to illustrate the grooves in the surface of the inker; and

Fig. 3 is a top view of the inker, the cap being broken away to show the distributing apertures in the core of the inker.

Referring to the drawings, the inker comprises a core 10 having an axial opening therethrough to accommodate a spindle 11 on which the inker is adapted to rotate. Spindle 11 is threaded into and supported on a fixed member 12 of the machine frame from which the core is spaced by a washer 13 and to which is secured a bracket 14 for supporting an ink reservoir 15. The reservoir is provided with an adjusting screw 16 for regulating the discharge of ink therefrom. A supply pipe 17 is positioned over the core and directs ink from the reservoir into a channel 18 in the upper face of core 10. The channel 18 is cut to provide a boss 19 at the upper end of the core thereby to prevent ink from reaching the spindle 11. The outer sides 21 of the channel are inclined upwardly and outwardly so that if the inker is rotated at sufficient speed, the ink in channel 18 will rise along the

sides 21 toward the upper and outer edge of the core. Overlying the top of the core is a cap 22 having an annular flange 23 adapted to form a tight fit with the top of the core 10 and be held frictionally thereon. The cap is also provided on its under face with a groove 24 so disposed with respect to the sides of channel 18 that it forms a continuation thereof. Groove 24 is U-shaped in cross section and inverted to direct ink back into channel 18 when thrown above the top edge of the core. The cap 22 has a large central aperture 25 through which ink from reservoir 15 is directed into channel 18.

Surrounding core 10 is a hollow cylindrical felt pad 26 supported on an annular shoulder 27 at the lower end of the core and adapted to fit snugly thereon. The outer periphery of the core is provided with a number of longitudinal vertical grooves 28 varying in length and each communicating with channel 18 through apertures 29 formed in the flange-like upper end of the core. These apertures are preferably inclined outwardly and downwardly toward the grooves 28.

The arrangement described provides for uniform distribution of ink throughout the pad in the following manner: Ink is discharged in regulated quantities from reservoir 15 through pipe 17 into channel 18 and, assuming that the inker is in contact with a moving die and rotating at a relatively high rate of speed, the ink rises along the inclined sides of the channel from which it flows through apertures 29 into the longitudinal groove 28. Any ink that flows past the apertures 29 is directed back to channel 18 by the inverted U-shaped groove 24 in cap 22. Since the grooves 28 vary in length, it is obvious that the ink flowing in the shorter grooves is absorbed by the upper portion of the pad 26, whereas that directed along the long grooves is conducted to the bottom of the pad, which is thus supplied with ink. The construction and arrangement of parts at the upper end of the inker protects the spindle from ink which if permitted to become gummy or hard would affect lubrication of the spindle and retard rotation of the inker.

It is obvious that the opening in the cap

22 is free from spider arms so that the flow of ink from pipe 17 is not obstructed and there is no danger of splashing therefrom. The ink is further confined against splashing by the grooved cap which returns ink that has risen above the top of the core during rotation.

While a preferred form of the invention has been described in detail and reference 10 made to its application to cancelling machines, it is apparent that its use and construction is not so limited. Such modifications as lie within the scope of the invention are, therefore, contemplated.

15 What is claimed is:—

1. A rotatable inker comprising a vertical cylindrical core having an annular channel in the upper face thereof, the outer peripheral surface of said core having a plurality 20 of longitudinal grooves thereon communicating with said channel; means for feeding ink to said channel; and an absorbent pad surrounding said core.

2. A rotatable inker comprising a vertical 25 cylindrical core having an annular channel in the upper face thereof, the sides of said channel being inclined upwardly and outwardly, the outer peripheral surfaces of said core having a plurality of longitudinal 30 grooves thereon, there being apertures adjacent the upper portion of said inclined sides to provide communication between the channel and said longitudinal grooves; means for feeding ink to said channel; and an absorbent 35 pad surrounding said core.

3. An inker comprising a vertical cylindrical core having an annular channel in the upper face thereof, the outer peripheral surface of said core having a plurality of longitudinal 40 grooves thereon communicating with said channel; a spindle on which said core is rotatably mounted; and axial boss at the upper end of said core extending above said channel, said spindle passing through said 45 boss; means for feeding ink to said channel; and an absorbent pad surrounding said core.

4. A rotatable inker comprising a vertical cylindrical core having an annular channel in the upper face thereof, the outer peripheral 50 surface of said core having a plurality of longitudinal grooves thereon communicating with the upper portion of said channel, said grooves varying in length; means for feeding ink to said channel; and an absorbent pad surrounding said core.

5. A rotatable inker comprising a vertical cylindrical core having an annular channel in the upper face thereof, the sides of said channel being inclined upwardly and outwardly, the outer peripheral surface of said core having a plurality of longitudinal 60 grooves thereon communicating with the upper portion of said channel; means for feeding ink to said channel; means cooperating with the upper end of said core for re- 65

turning ink elevated by centrifugal force to said channel; and an absorbent pad surrounding said core.

In testimony whereof I have signed my name to this specification.

JOSEF V. PACHER.
